MACHINE FOR IMPALING, FEEDING, AND SLICING COMMODITIES

Henry Leon Bird and Arthur Rose,
Arlington, Calif.

Application September 17, 1945, Serial No. 616,772

2 Claims. (Cl. 146—111)

1

This invention relates to slicing machines generally and specifically to a type of slicing machine adapted to rapidly cut a mass so as to produce individual units of a given size.

Specifically, the invention is directed to a slicing machine which will cut to form a product of a glutinous nature. Such a product is elastic, exceedingly tenacious, resists cutting and may be deformed during a cutting operation. By way of example, health food stores now offer for consumption a substance known as gluten. This gluten may be cooked to produce what is known as a gluten steak of high nutritive value. The present slicing machine is particularly adapted to cut gluten into any desired slice thickness to provide steaks ready for cooking. As a rule, gluten is formed in a long roll of some definite diameter and the slices are cut from this roll by hand. This is a tedious operation, the slices vary as to thickness and the gluten is difficult to handle.

An object of the present invention is the provision of a slicing machine particularly adapted to the cutting of masses which are elastic and tenacious in character with great rapidity and accuracy in the desired cut.

Another object is the provision of a slicing machine which requires little personal attention after it is once set in operation. As rapidly as the work is fed to the machine, the machine will perform its cutting operation. Hence a single attendant is all that is necessary for successful use of the machine.

Another object of the invention is the provision in a slicing machine of a positive means for feeding the work to be cut, and wherein the work is securely held during the feeding operation.

Another object is the provision of a slicing machine which incorporates a novel means for directing work to a cutter and wherein the work is advanced toward said cutter in accordance with cutter speed.

Another object is the provision of a slicing machine adapted to handle elastic and glutinous masses which normally compress easily in such a manner as to overcome any inherent compression in the mass, to the end that cutting thereof may be performed with predetermined accuracy.

Other objects include a slicing machine which is compact, readily placed in use at a selected location, foolproof in operation, of few moving parts and generally superior to slicing machines of the automatic feed type now known to the inventors.

With the above and other objects in view, the

2

invention consists in the novel and useful provision, formation, construction, association and relative arrangement of parts, members and features, all as shown in a certain embodiment in the accompanying drawings, described generally and more particularly pointed out in the claims.

In the drawings:

Fig. 1 is a top plan view of the slicing machine;

Fig. 2 is a side elevation of the slicing machine shown in Fig. 1;

Fig. 3 is a front elevation looking in the direction of the arrow 3 of Fig. 2;

Fig. 4 is an enlarged detail, partially in section, of one of the feed elements of the invention;

Fig. 5 is a fragmentary sectional view of means for actuating the feed elements of the invention;

Fig. 6 is a fragmentary detail of a drive means for the feed elements;

Fig. 7 is a perspective view of one of the blade elements of the invention;

Fig. 8 is a fragmentary detail, partly in section, of a blade element; and,

Fig. 9 is a fragmentary side elevation of a belt tightening means.

25 Referring now to the drawings:

The improved slicing machine is shown in one embodiment and designated as an entirety by 1. The said machine includes an elongated trough 2 which in the present instance has the appearance of an open channel in cross section, as shown in Fig. 3 at 3; a rotary knife 4, constituting a wheel provided with a plurality of radially arranged blades 5 adapted to cut material fed through the trough 2, as indicated at 6, together with feed means 7 constituting impaling devices or picks mounted for movement relative to the trough and in such a manner as to impale any work within the trough and move said work progressively toward the rotary knife 4. The invention further contemplates suitable means for actuating the aforementioned instrumentalities.

The slicing machine has its various operating parts so coordinated as to occupy a small space and to be suitably carried upon a framing designated generally as 8. This framing includes pairs of legs, one pair being designated as 9 and the other pair as 10, with interconnecting pieces 11 joining pairs of said legs, which interconnecting pieces are provided with rollers 12 whereby the framing and mechanism carried thereby may be moved. Framing members 13 and 14 transversely extend between members 10, and like framing members which are indicated at 15 and 16 extend between the members 9. To properly

brace members 9 and 10, interconnecting frame members of the character shown at 17 are provided. It is to be observed upon reference to Fig. 2 that a portion of members 10 is substantially in right angular relationship to members 11, while a second portion of members 10 is at an angle as shown at 10a. The angularity of part 10a corresponds to the angularity assumed by members 9 relative to members 11, members 10a and 9 being substantially parallel. Supported by the members 14 and 16 and extending transversely therebetween is an open-centered elongated rectangular framing 18.

The gluten or other elastic mass to be cut is preferably rolled to cylindrical form so as to fit within the trough 2. This trough is conventional in form and in the present instance is channel-like in cross section, as indicated by the line 19 in Fig. 3. The gluten is placed in this channel and is adapted to be progressively moved therewith by means of the impaling devices or picks 7. Usually the trough is flushed with a liquid such as water so that the gluten will not stick thereto. This trough is supported by the framing 18 and extends transversely between upper framing members 14 and 16.

It is intended that the rotary knife 4 should be in such a position as to have the knife members 5 thereof contiguous to the trough end 6. The trough at this end is provided with a shear plate 21. This shear plate has an opening 22 which corresponds to the channel section of the trough and has a transverse portion at 23 which extends above the top edges of said trough. The rotary knife includes a disc 24, an annulus or ring 25 spaced from the circumference of said disc to provide an annular way 26, and blades 5 spanning the way. The blades 5 are substantially radially arranged and are of the form shown in Figs. 7 and 8. Specifically, each blade includes an elongated member reduced in thickness at its ends 27 and 28 and provided with a beveled edge portion 29 to thereby provide a knife edge at 30. The reduced portions 27 and 28 are transversely perforated at 31 and 32, whereby said blades may be secured between the disc 24 and the annulus 25. By reducing the thickness of the ends of the blades shown at 27 and 28, shoulders are formed as indicated at 33 and 34. The blades are interposed between the disc 24 and the annulus 25 so that the edge of the disc and the inner edge of the annulus bear against the shoulders 33 and 34 respectively, the reduced thickness end portions 27 and 28 overlapping the annulus and the disc. Suitable means such as screws or rivets are passed through the perforations 31 and 32 and into the disc and annulus for securing the blades in position of service. The spacing between the blades is such that when one blade has completed its passage over the shear plate another blade is commencing its passage thereover. Other blade spacing may be resorted to, depending upon the speed with which the material to be cut is fed.

Shaft 35 is reduced in diameter at one end, and disc 24 is axially mounted thereon. The shaft 35 is suitably supported in bearings 36 and 37 secured to the frame members 14 and 16. The reduced end portion is partially screwthreaded so as to receive a nut 39. The disc 24 is held between two washers 40 and 41, and when the nut 39 is tightened the washer 41 will engage the annular shoulder formed by the different diameter portions of the shaft, thus clamping the disc.

To prevent end play in the shaft, washers are secured to the shaft at 42 and 43.

The shaft 35 at the end opposite the rotary knife carries pulley wheels 44 and 45.

Extending between the framing members 13 and 15 is a platform 46. Carried on the platform is a motor 47, the shaft of which carries a gear 48. Gear 48 meshes with gear 49 mounted on shaft 50, the shaft 50 being carried on pedestal type bearing members extending from the platform 46, as shown at 51 and 52. Shaft 50 carries at one end a pulley 53.

A shaft 54 is mounted in bearings 55 and 56 carried on framing members 14 and 16. The outermost end of said shaft 54 carries a pulley wheel 57. A continuous belt 58 is passed between pulley wheels 44 and 57. Shaft 54 carries a pulley wheel 59 and a continuous belt 60 is passed between said pulley wheel and pulley wheel 53. Thus when the motor is energized the rotary knife will be driven at a selected speed, with the base faces 61 of each blade sweeping over the shear plate 23.

The means for feeding the work to be cut along the trough include spaced impaling devices or picks 7. These picks are of the form shown in Fig. 4, and wherein a rod has two portions 62 and 63 interconnected by an offset 64, whereby portions 62 and 63 are substantially parallel, and a pointed member 65 is in substantially right angular relationship to part 62. Part 63 carries a weight 66.

The construction is such that the pick is adapted to be moved from the position shown in Fig. 4 to a position at right angles to said showing in the actual use of the device. The picks of impaling devices 7 are adapted to be spacedly mounted on hinges designated generally as 67, which hinges include two strap members 68 and 69 interconnected by the usual knuckle and pin 70, the part 62 of the pick being secured to hinged strap 68 as by welding, as indicated at 71, while the other strap 69 is riveted or otherwise secured transversely to a belt 72. This belt constitutes a part of means for progressively moving the picks so that the picks when properly actuated may impale the article to be fed through the trough toward the rotary knife.

An angle iron 73 extends transversely between the frame members 14 and 16. One end of said member 73 carries a bearing 74, while the opposite end is provided with an adjustable extension 75. (See Fig. 9.) Extension 75 is provided with a bearing 76. Pulleys 77, 78 are mounted on shafts 79, 80 carried in bearings 76, 74. The continuous belt 72 is carried between the pulleys 77, 78. The shaft 80 is passed through bearing 81, secured to one end of frame 18. A bevel gear 82 carried by shaft 80 meshes with gear 83 secured to shaft 84. Suitable bearings secured to the framing 18 support shaft 84, as indicated at 85. Suitable supports 86 carry bearings 87 and 88 for a jack-shaft 89. A pulley 90 and a gear 91 are mounted on the shaft. The shaft 84 carries gear 92, which meshes with gear 91. A continuous belt 93 is passed between pulleys 45 and 90.

The belt 72 may be provided on the inner surface thereof with a plurality of spaced transverse cleats 94, see Fig. 6. These cleats assure a positive movement of the belt and prevent slippage of the belt around the pulleys 77 and 78. Each pulley is provided with spaced transversely extending grooves 95 adapted to receive the cleats 75 as the belt passes around the pulleys. Each cleat

is formed with a longitudinally extending groove 96. It will be observed that the cleat is on a side of the belt opposite one of the leaves 69 of the hinge, and that the part 63 of the pick is adapted to be received within the transverse groove 96 of the cleat. In this manner the part 63 does not interfere with movement of the belt in its passage around the pulleys. As each pick is weighted, as shown at 66, the picks tend to maintain the position illustrated in Fig. 4. In the present invention the picks however are moved positively so as to have the sharpened end 65 thereof forcibly driven into the commodity to be moved along the trough 2. This is accomplished by providing a rod 97 suitably supported by means of brackets 98 and 99. The brackets are supported by a framing member 100 transversely mounted between the framing members 14 and 16, see Fig. 3. It is to be noted that the brackets extend upwardly between two stretches of the belt 72. The rod 97 has an extended portion 101, and a cam portion 102, which latter portion is formed by curving the said rod upwardly and inwardly, as best shown in Figs. 1 and 2. The portion 101 parallels the sides of the trough and is spaced slightly thereabove. The portion 102 curves inwardly toward the axis of shaft 79. Thus when the pulleys 77 and 78 are being rotated, the belt 72 is moved and the end portion 102 of the rod 97 will engage the part 62 on each pick and swing the pick downwardly about its hinged point, as illustrated for several positions of the pick members in Fig. 3, until the pick parts 62 and 63 assume a horizontal position or a position transverse to the trough. When this occurs the sharpened ends 65 will be substantially centrally received within the trough and the depth vertically thereof, see Fig. 1. The rod part 101 terminates a short distance inwardly from the trough end, substantially at a distance equal to the spacing between two picks. When a pick reaches the end of the rod, the weight 66 tends to erect the same to the position shown in Fig. 4. However, the erection may not be rapid enough if the belt is travelling at a high speed, and to assure proper erection a further cam rod is provided at 103, see Figs. 2 and 5. One end of the rod 103 is secured to bracket 98, as by means of a clamp 104, while the opposite end is fastened to the framing 18, at 105. Rod 103 has a curve of small radius and is adapted to be brought into contact with weight 66 of each pick to cam the pick to an upright position, see the position shown in Fig. 4.

Adjustably carried by framing member 18 through the medium of a shiftable bracket 106, is a gauge plate 107. This gauge plate by means of the adjustment allowed the bracket may be held at any desired spacing from the exterior surface of rotary knife 4, see Fig. 5.

The operation, uses and advantages of the invention are as follows:

When the motor is energized all of the parts are set in motion, to wit: the rotary knife will turn at a selected speed, the belt 72 will move transversely of the pulleys 77 and 78, and the pick members will move from an upright position to a horizontal position so as to transversely impale any material within the trough 2, and move said material toward the end of the trough at such a rate that the rotary blade will slice the same.

If gluten is the material to be sliced, a suitable kettle is placed at 108 so that slices of material may drop within the said kettle. As a rule, the kettle is filled with a hot liquid, such as water,

which tends to cook the surface of the gluten slices, to the end that they do not stick together. It will be observed from Fig. 2 that the slicing machine inclines downwardly toward the discharge end of the trough. This construction is used in order to assist movement of the material within the trough and to allow the slices to fall free of the knives.

If the material to be cut is gluten, the gluten is rolled to form so as to fit within the trough. The trough is elongated and extends beyond the pulley 77, so as to permit an operator to insert in the trough rolls of gluten prior to the picks contacting the gluten. This trough is flushed with water so that feeding of the gluten will be facilitated, and to accomplish this we have illustrated in the figures an overhead spray pipe 200 positioned centrally of the trough. As the belt 72 moves, the picks are actuated by the cam portion 102 so as to bring the sharpened ends 65 into penetrating engagement with the gluten body. These pick ends then move the gluten body along the trough so that an end of said body may be projected beyond the shear plate and into engagement with the gauge plate prior to a cutter blade engaging the gluten. The blade then passes through the gluten to cut a slice from the main body, which slice drops within the liquid in kettle 108. Each pick as it nears the end of part 101 of rod 97 is forcibly removed from the gluten by being actuated to a vertical position through the medium of the cam rod 103. As previously stated, this action is very sudden and abrupt and must be accomplished just prior to the gluten being sliced by the rotary knife. Gluten and substances of a similar nature compress easily, are rubbery and are difficult to slice, or at least to produce a slice of uniform thickness. It has been found that travelling conveyor belts, plunger methods or attempts to squeeze material through a tube are not successful, and the present means shown and described of providing picks at spaced points for moving the gluten has performed in a successful manner and without the gluten compressing or "bunching." The present machine operates rapidly and is capable of cutting 350 slices of gluten per minute, utilizing one operator to place the gluten in the elongated trough. The cutter blades are easily removed from the rotary knife for sharpening or replacement. In order to assure that the rotary knife will not develop any wobble or uneven movement, a bracket 109 is secured to the framing, and an angled end of said bracket carries a pressure roller 110 adapted to have contact with the outer face of the annulus 25. This roller has contact with said face adjacent one side of the pressure plate 21, see Fig. 3.

The device as an entirety may be easily shifted on the dirigible framing provided for this purpose.

We claim:

1. In a gluten slicing machine, an elongated U-sectioned trough having a smooth-surfaced interior, a shear plate at one end of said trough, a gauge plate contiguous to the shear plate, and a rotary knife interposed between the shear plate and the gauge plate, comprising a plurality of spaced radial blades adapted for sweeping movement across the shear plate; said trough adapted to hold an elongated roll of gluten, and picks adapted to be received within the trough to impale the gluten roll transversely throughout its length, and means for causing simultaneous movement of all the picks toward the shear

plate to move the gluten roll between the radial blades and against the gauge plate.

2. In a gluten slicing machine, an elongated U-sectioned trough having a smooth-surfaced interior, a shear plate at one end of said trough, a gauge plate contiguous to the shear plate, and a rotary knife interposed between the shear plate and the gauge plate, comprising a plurality of spaced radial blades adapted for sweeping movement across the shear plate; said trough adapted to hold an elongated roll of gluten, picks adapted to be received within the trough to impale the gluten roll transversely throughout its length, means for causing simultaneous movement of all the picks toward the shear plate to move the gluten roll between the radial blades and against the gauge plate, and means for the trough for supplying a wetting agent thereto during movement of the gluten roll.
